Artemus W. Goddard

United States Patent Office.

ARTEMAS W. GODDARD, OF CLINTON, MASSACHUSETTS.

Letters Patent No. 65,900, dated June 18, 1867.

IMPROVEMENT IN CALIPER-RULES.

The Schedule referred to in these Letters Patent and making part of the same.

TO ALL WHOM IT MAY CONCERN:

Be it known that I, ARTEMAS W. GODDARD, of the town of Clinton, and county of Worcester, and State of Massachusetts, have invented a new and useful Improvement in Caliper-Rules; and I do hereby declare that the following is a full, clear, and exact description of the construction and operation of the same, reference being had to the annexed drawings, making a part of this specification, in which—

Figure 1 is a view of the rule when open for use.

Figure 2 is a plan of the caliper-rule.

Figure 3 is a detailed view to be hereinafter referred to.

The present invention relates to a new and useful improvement in caliper-rules for measuring diameters; and consists, first, in the employment of two blades of steel, or any other suitable material, so attached to the rule that they shall, when opened to their full extent, answer the purpose specified; second, in the combination of these two blades with a sliding gauge, said gauge to be used for ascertaining the diameter of an object after having been spanned by the blades; third, in the employment of rubber-cloth packing between the blades and the parts of the rule to which they are fastened to prevent the blades from becoming loose by the wear of the rivets. The packing is put with the cloth side against the blades, and the rubber side resting on the wood, thereby preventing the blades, when being opened, from adhering to the rubber.

In the accompanying plate of drawings I have represented my invention, reference being had to the same in the following description:

a a represent the blades, which, when open, in combination with the rule and the joint *f*, fig. 1, form the caliper. *b*, fig. 2, shows the position of the blades when not required for use as calipers. *c c* are slots in the blades *a a* for the insertion of the thumb-nail when opening them for use. *d d*, figs. 2 and 3, represent the corner of the rule as cut away to uncover the slots *c c* in blades *a a*. The blades *a a* are fastened to the rule by the rivets *g g*, figs. 2 and 3, and the wood is cut away, as shown at *e*, fig. 2, so that the surface of the blades *a a* shall not be any above the surface of the rule, which would prevent the closing of the parts *h h*, fig. 2, in a proper manner. *m*, fig. 3, shows the rubber-cloth packing between the blades *a a* and the body of the rule.

Having described the manner in which the devices composing my invention are arranged, I will proceed to describe how the same operate together.

To ascertain the diameter of an object the rule, fig. 1, is grasped at the points *i i* and opened, as shown, the thumb-nail is inserted in the slots *c c*, and the blades *a a* opened to their full extent, the object is calipered, and the graduated slide *k* is drawn out, and the distance between the points *l l* is ascertained by measurement.

Having described my invention, I claim as new, and desire to secure by Letters Patent—

1. The blades *a a*, when arranged as and for the purpose described.
2. The combined caliper and slide-gauge rule, when arranged substantially as and for the purpose set forth.

ARTEMAS W. GODDARD.
